COOLING TOWER FOR LIQUIDS**Artur Odenthal, Bochum, Germany, assignor to Maschinenbau-Aktiengesellschaft Balcke, Bochum, Germany****Application July 24, 1952, Serial No. 300,570****Claims priority, application Germany May 2, 1952****3 Claims. (Cl. 261—112)**

The invention relates to cooling towers for cooling a liquid such as water by means of a gaseous medium such as air. There are two types of such cooling towers. In the first type, the so-called louvred type, the cooling elements are long small slats of wood or another substance adapted to resist the corroding influence of aggressive constituents of the liquid to be cooled. These slats have usually a width of two to four inches and are horizontally arranged side by side with predetermined spaces therebetween.

In the other type to which the invention relates, the cooling elements consist of vertical or at least approximately vertical plates. The liquid to be cooled is applied by suitable means to the side surfaces of these plates and runs on these surfaces downward in a continuous thin film. Thereby, the liquid is not sprayed or atomised as at the louvred coolers, but trickles down from the lower edges of the plates of one set onto the upper edges of the plates of the next set and so on. In cooling towers of the type having cooling plates, the loss of liquid mechanically carried along with the gaseous cooling medium is small in comparison with that in cooling towers of the louvred type.

The main object of the invention is to effect automatically a substantial vertical position of the cooling plates after they are inserted into the frame structure of the cooling tower.

As it is clear to those skilled in the art, the maximum cooling effect is obtained with cooling plates of predetermined cooling surfaces, if these plates are in a substantially vertical position.

Another object of the invention is the spacing of the cooling plates in an effective and convenient manner. This spacing may differ in one section of the cooling tower from the spacing in another section. The spacing must be predetermined and ensured by suitable means which afford a proper quantity of cooling air to flow through the space between two adjacent plates, the side surfaces of the plates being covered with a thin film of the liquid to be cooled.

A further object of the invention is to facilitate the mounting of the cooling plates in the frame structure of the cooling tower.

The means and manner to attain these goals and other advantageous features of the invention are explained with reference to the accompanying drawings illustrating a preferred embodiment of the invention.

Fig. 1 perspective and schematically shows parts of a cooling tower of the plate type,

Fig. 2 illustrates a part of a cooling plate with a spacing element attached thereon,

Fig. 3 is a front view of a spacing element,

Fig. 4 is a part sectional end view of the upper parts of some cooling plates with spacing elements, the section being made along line IV—IV of Fig. 2,

Fig. 5 is a perspective illustration of a portion of a set of modified cooling plates according to the invention.

A cooling tower with cooling plates 5 is provided with side wall members and liquid distributing members

adapted to apply the liquid to be cooled to the side surfaces of the plates 5. These members, being of the usual type, are not shown in the drawings. The plates 5 are of rectangular shape, the shorter edges thereof having a length of at least one yard and the other edges having a length twice or more of the length of the smaller edges. Thereby, the sides of a plate, i. e. the cooling surface thereof have an area of at least 40 square feet. The plates are provided with protruding portions 5a at these ends. As shown at the left side of Fig. 1, these portions 5a are arranged on the short sides of the plates, and as shown at the right side of this figure, they are arranged on the long sides of the longitudinal plates. With their protruding portions, the plates rest loosely upon horizontally elongated and parallel beams 4 of the frame structure. At right angles to the beams 4, there are horizontally elongated and parallel beams 4a arranged on the frame structure, vertical posts 1 or horizontal ledges 3 upwardly extending from the beams.

All plates 5 resting loosely upon a pair of parallel beams 4 are arranged in groups or sets by means of the intersecting cross beams 4a, as shown in Fig. 1. Each beam 4a with its protruding portion 1 or 3 respectively forms a spacer between two sets of plates 5, the groups of aligned plates being spaced from each other by means of the beams 4. Each set contains an odd number of plates 5. Apertures 6 are provided in the odd-numbered plates. As illustrated in Fig. 1, the holes 6 are aligned to form parallel transverse rows within each set of plates 5. Spacers 2 are inserted into the holes 6 (Fig. 2) forming parallel transverse rows of spacers within each set. The ends of these spacer rows abut against the protruding upper portions of the adjacent beams 4a.

Each spacer 2 has two parallel plates or discs 8 connected by a rodlike spacer portion 7 attached eccentrically to the even inner sides of the plates 2. When inserted into the apertures or holes 6, the spacers 2 rest with their portions 7 upon the lower edges of the holes, the plate portions 8 being astride the respective cooling plates, forming rows of spacers beneath the corresponding lines of the rows of the holes 6 (Fig. 4). A top portion 1 or 3 of a beam 4a abuts against the spacer plates or discs 8 on the outer side of an adjacent plate 5 (Fig. 1). At the abutting places, a protruding portion 1 or 3 may be provided with suitable members such as screw bolts 9 to adjust the distances between the outermost spacer plates 8 and the portions 1 or 3.

Instead of loosely inserted spacers 2, the plates 5 may be provided with ledges, selvages, ribs, brackets, noses or the like on their sides working as spacers between two adjacent plates. These spacing members may be integral parts of the cooling plates for example protuberances as designated by numeral 10 in Fig. 5 or separate members rigidly attached onto the sides of the plates. The plates 5 are preferably made of mineral substances such as asbestos-cement adapted to resist the corroding influences of aggressive constituents of the liquid to be cooled. In many cases the liquid to be cooled has aggressive acid or basic constituents.

The distances between two adjacent cooling plates 5 are fixed by the thickness of the spacer plates or discs 8 or their substitutes at a predetermined rate. These distances may be varied at the several sets of cooling plates and also within the sets themselves. Thereby, the quantities of the gaseous medium flowing through the spaces between the cooling plates can be conveniently regulated. Preferably, cooling plates of great size are used. In this case, all sets of these plates may be arranged at the same level on the frame structure, as shown in Fig. 1. Thereby, the mounting of the cooling plates is facilitated and is effected more quickly than in conventional cooling towers. Furthermore, no special means are needed for holding the cooling plates in a proper, i. e. in a vertical position,

when inserted into the frame structure of the cooling tower.

What I claim is:

1. A cooling tower comprising a frame structure including first substantially horizontal beams and second substantially horizontal beams disposed at an angle to said first beams, a plurality of sets of individual parallel and substantially vertical cooling plates, said plates having laterally protruding marginal portions resting on opposite ones of said beams, and spacing means individually loosely supported by and extending from the surface of every other of said plates and abutting against the surfaces of the two neighboring plates which surfaces individually face the surfaces of the plates supporting the spacing means, said frame structure including spacer portions extending vertically upwards from said substantially horizontal beams and being abutted by the spacing means supported by the plates at the extreme ends of said sets.

2. A cooling tower comprising a frame structure including first substantially horizontal beams and second substantially horizontal beams disposed at an angle to said first beams, a plurality of sets of individual parallel and substantially vertical cooling plates, said plates having laterally protruding marginal portions resting on opposite ones of said beams, and spacing means individually including two plate portions and a spacer portion interconnecting said plate portions and having a cross section smaller than said plate portions and spacing said plate portions as far as the thickness of said cooling plates, said cooling plates having apertures affording passage of said plate portions through said apertures, said plate portions being astride of the respective cooling plate and said spacer portions being supported by said cooling plates in said apertures, said spacing means being aligned to form a plurality of rows transversely extending through the cooling plates of a set of cooling plates, maintaining abutting relation of all spacing means and cooling plates

along said rows, said frame structure including spacer portions extending vertically upwards from said substantially horizontal means and being abutted by the spacing means supported by the plates at the extreme ends of said sets.

3. A cooling tower comprising a frame structure including first substantially horizontal beams and second substantially horizontal beams disposed at an angle to said first beams, a plurality of sets of individual parallel and substantially vertical cooling plates, said plates having laterally protruding marginal portions resting on opposite ones of said beams, said plates having apertures which are aligned to form a plurality of rows transversely extending through the cooling plates of a set of cooling plates, and spacing means having portions substantially conforming with said apertures and adapted to be passed therethrough and being astride of the respective plates when said spacing means are in operating position, said frame structure including spacer portions extending vertically upwards from said substantially horizontal beams and being abutted by the spacing means supported by the plates at the extreme ends of said sets.
